GAME APPARATUS

Rae J. Heymer, Minneapolis, Minn.

Application March 4, 1938, Serial No. 193,899

3 Claims. (Cl. 273—85)

This invention relates to game apparatus, and particularly to game apparatus where a ball or projectile is impelled or thrown at a target preferably disposed in such manner that the ball will be thrown through the air rather than rolled or impelled along a supporting surface.

It is an object of my invention to provide game apparatus of the class referred to wherein the skill and accuracy of the players are largely responsible for the winning of the game, but where chance determines the various positions from which the ball is thrown and also preferably the turns of the players in making their shots.

My game apparatus is particularly adapted for a parlor basketball game where almost the identical rules of basketball can apply, and where the chances of skilled players successfully making the various shots, as well as the frequency of the turns or plays of each player are approximately the same as in the actual game of basketball as it is played in the United States. My apparatus is, however, very well adapted for various other games having different rules.

It is a further object to provide in game apparatus of the class described a simple and efficient impeller which may be directionally positioned or aimed with respect to the target, and bodily moved to a number of predetermined positions, in combination with a ball or projectile having means associated therewith, preferably a plurality of facets formed on the ball, whereby the next play and position of shooting is dependent upon the position of the ball when it comes to rest after the preceding shot, without requiring any additional or extraneous means of chance such as the throwing of dice, spinning of a spinner or calculating device for determining the same.

Another object is the provision of an improved game apparatus utilizing a playing board and one or more targets disposed when the game is played in an elevated position above the board with a simple, but highly efficient impeller for throwing the ball through various arcuate paths, all of which may be quickly assembled for playing and may be knocked down into very compact position for sale or shipment.

A more specific object is the provision of game apparatus including a playing board and target elevated above the playing board, wherein indicated predetermined positions on the board with reference to the target represent various shots or positions which are found in such games as basketball, golf, etc., and wherein the skill of the player in hitting the target depends upon his accuracy and experience in properly positioning the

shooter directionally with respect to the target, as well as upon the amount of force with which the impeller is manually stricken, some of said shots from the predetermined positions being more difficult to make than others.

These and other objects and advantages of my invention will be more fully set forth in the following description made in connection with the accompanying drawings, in which like reference characters refer to the same or similar parts throughout the various views, and in which:

Fig. 1 is a top plan view of one form of my apparatus intended for use by from two to four players, set up for play, one of the shooters or impellers being positioned to direct the ball toward target number 1.

Fig. 2 is a vertical section taken approximately on the line 2—2 of Fig. 1;

Fig. 3 is a top plan view of one of the shooters;

Fig. 4 is a vertical section taken on the line 4—4 of Fig. 3, dotted lines indicating the moved position of the shooter in action, as well as the position of the ball and a portion of the various arcuate travels thereof;

Fig. 5 is a side elevation of a suitable ball or projectile and Figs. 6 and 7 are opposite end elevations of the same;

Fig. 8 is a front elevation of a somewhat different form of my invention adapted for use by one or two players and set up in playing position, a portion of one corner of the playing floor being broken away;

Fig. 9 is a fragmentary plan view of the playing field including the back, target and playing floor knocked down into compact flat position for selling or shipment;

Fig. 10 is a front elevation of a somewhat different form of ball which is especially adapted for use with the form of my invention shown in Figs. 8 and 9; and

Fig. 11 is a fragmentary top plan view of a somewhat different form of playing board which may be utilized with a spherical ball or projectile.

In the embodiment of the invention illustrated in Figs. 1 to 7, inclusive, I provide a playing floor in the shape of a cross which may conveniently be made up of four floor sections 13, shaped as clearly shown in Fig. 1 in such manner that the angled forward extremities may fit together to form the shape of a cross when the floor is set up. For convenience, the floor sections 13 may be hinged together in pairs by suitable hinge strips 14 secured to the undersides thereof to facilitate compact disposal of the apparatus when the same is not in use. The several floor sections are pro-

vided with flanges or rims which collectively form a low guard wall around the entire playing field to diminish the chance of the ball from jumping or rolling off the board. Each of the floor sections 13 are marked off in the manner of an actual basketball floor to define a foul alley 15 and a foul line 16. The several sections are printed with appropriate identification, as shown, with the enlarged numerals from 1 to 4, the numerals 10 preferably being printed in different colors, such as, for example: red, green, blue and yellow. On each of the floor sections is also printed a series of predetermined positions defined as shown by circles and as shown in Fig. 1, being identified with the numerals 1, 2, 3, 4, 5, 6, 7, 8, 9 and 0.

15 The several floor sections 13 carry adjacent their inner extremities upstanding pegs 13b which are adapted when the sections are operatively positioned, to engage apertured portions of a 20 square pedestal 17 to secure the same centrally of the board and to support by means of a detachable post 18 the bank boards and baskets. The bank boards for the several baskets may be conveniently constructed in the form of a collapsible 25 open-ended box 19 which when distended may snugly fit and be supported upon a square bracket 20 detachably and telescopically secured to the upper end of the post 18. The baskets, as shown, comprise wire frames 21 having attachment lugs 30 21a extending therefrom and engageable with holes through the bank walls 19 and through the edges of the square bracket 20. The lugs 21 of the baskets thus retain the bank boards and baskets in proper position for play. The basket nettings 35 22 are hemmed to fit upon and be supported by the basket frames.

I provide a very simple, but scientific impeller or shooter in the form of an integrally constructed plate 23, best shown in Figs. 3 and 4. Preferably one of these impellers is provided for each player. The plate 23 is preferably constructed from some suitable rigid material such as sheet metal and has an upwardly angled striking end 23, which as shown in Fig. 3 may be tapered toward its extremity to facilitate accuracy in striking the longitudinal center when a play is made. The body of the shooter 23 is purposely arced, terminating at its ball receiving end in a down-turned lip 23b which engages the board or floor prior to making a shot. A round aperture 23c is formed in the rear end of the shooter to receive the ball or projectile. In making a shot from one of the predetermined positions on the floor, the shooter 23 is directionally positioned to the best ability of the player in such manner that it will be aligned with a point on the banking wall 19 to make possible a successful bank shot at the target or basket. The aperture 23c in the shooter is positioned just above the appropriate circle on the playing floor. The angled portion 55 23d of the shooter engages the playing floor, forming a fulcrum, and the curved body of the impeller with the ball held in the rear declined portion of the curve, enables the ball to be thrown through a rather high arc to facilitate banking of the ball against the walls 19 and reproducing accurately the play in an actual basketball game.

60 A suitable form of projectile or ball 24, as illustrated in Figs. 5 to 7, comprising a member having the general shape of a sphere, but provided with a plurality of diametrically opposed, circumferentially arranged facets 24a having plane surfaces upon any one of which the ball may rest after it has been thrown at the target and 65 has bounced and rolled upon the playing floor.

In the form shown in Figs. 1 and 2, a ball is preferably provided for each contestant, colored or otherwise identified to match the color of one of the large numerals identifying the four playing sections. Each ball is marked, preferably with 5 the identification of a number of the predetermined positions marked out on the four playing sections. Thus, if four balls are used, each will carry on the facets 24a, the identification corresponding to one-fourth of the total number of 10 predetermined positions on the four floor sections and the facet of the ball which is uppermost when the projectile comes to rest after a shot, determines which player has the next shot and from what position that player shoots. For 15 example (see Fig. 5), if the facet having the numerals 2-0 is uppermost, this means that player number 2 takes the next shot from position 0 on the playing field, etc. The ends of the ball illustrated in Figs. 5 to 7 are preferably flattened at 24d 20 so that the ball may occasionally stop on one of the ends thereof, indicating that a foul has been made. These flattened ends may be colored to correspond with the coloring of the various numerals on the several playing sections and when the 25 ball stops with the color red uppermost, this means that the player having the red number takes the next shot from the foul position at the appropriate target.

30 In playing the game of basketball with this apparatus, the general rules for actual basketball are very closely followed. With the form of the invention shown in Figs. 1 and 2, two or four contestants may play. If two play, each takes two colors or two playing sections. The object of the game, of course, is to shoot the greatest number of baskets and fouls during the playing period decided upon for the game. Each basket shot from the field scores 2 points and each foul shot scores 1 point. Should the game result in a tie, 40 the two leading players take the positions 1 and 2 at the table and play a two minute overtime period. To start the game, one of the balls is tossed on to the playing field and after coming to a complete stop, indicates by the numbers 45 which turn up, the player who shoots first, and also designates the shooting position of that player on his field. The player then properly positions his shooter 23 on the board with the aperture 23c disposed over the appropriate circle on the 50 playing section and strikes the tip 23a of the shooter with the forefinger, skill and practice determining the proper force to be used for the various shots from the several predetermined positions. Skill is required in aiming the shooter 55 properly for the bank shots, as well as in using the proper degree of force for the various shots. The successive shots and indications of the turns of the players are indicated by the facet of the ball turning up after the preceding shot. Each 60 player uses his own ball when he shoots.

A game of basket golf may be played with the apparatus, with one or more persons and 9 predetermined positions marked out upon each section of the playing field, representing 9 holes of a golf course. Each player starts at the number 1 position on his section and shoots for the basket from that position until he sinks his shot. He then moves to the number 2 position and attempts to make the basket and so on until the 9 baskets are 70 completed. The player scores the number of shots for each position, and in competition the player completing the 9 baskets with the low score is the winner.

In Figs. 8 and 9 I have illustrated a very sim- 75

plified and inexpensive form of my apparatus especially adapted for use as a premium by large manufacturers as well as for sale in stores selling low priced merchandise. The entire playing field, including the floor, guard wall and banking wall, is collapsible into a flat package having the thickness of only three plies of cardboard or other suitable sheet material. In this form only one floor section, one banking wall and one basket are utilized. The playing floor and guard flange or wall may be constructed from a single sheet of cardboard or other suitable material 30 having the foul alley, the foul line and a number of predetermined shooting positions printed thereon. The edges of the sheet 30 may be scored for folding along lines *l* and *m* and the corners may be slit along the lines *n* so that the tab may be folded over the adjacent edge of one of the sides to form a very shallow box, as will be clear from an inspection of Fig. 8. The ends may be secured together by suitable means such as the common paper fasteners 31, registering apertures being provided in the joined edges. A back wall 32 furnishing the banking surface is provided having folded supporting sides 32a, preferably integrally formed therewith and adapted to be folded flush against the back wall when the apparatus is taken down for shipment or disposal. The side walls 30a fit within the flanges afforded by the marginal portions of the playing floor and may be secured rigidly therewith by paper fasteners, registering apertures being provided in the lower edges of such side walls and in the flanges of the playing floor. The basket has a wire frame 33 generally similar to the basket frame, in the form of my invention first described, terminating in elongated attachment portions which, when the device is first set up, are bent at right angles to the plane of the loop of the frame and may be projected through apertures in the back wall 32, and the ends of said attachment lugs are secured beneath keepers 34 which are formed from struck up portions on the back of the back wall 32. The basket netting is similar to that shown in the form first described. The game is played in the same way generally as in the form first described, both or all players utilizing the same playing floor, and a ball or projectile being provided for each of the players.

In Fig. 10 a slightly different form of projectile is shown, having a fewer number of facets corresponding to the predetermined positions printed on the playing floor, as shown in Fig. 9, and this projectile or ball is not provided as illustrated, with flattened end portions for determining foul shots.

This ball is particularly designed after the form of my invention shown in Figs. 8 and 9, having its facets identified in conformance to the positions printed upon the playing floor 30.

In Fig. 11 a corner of a modified form of playing floor is illustrated in top plan. This form of playing floor is adapted for use with a round ball which freely rolls, and which is not provided with indicating facets. The floor is declined toward the rear of the board so that the ball may roll and lodge in one of the several recessed portions 40. Each recess portion has identifying numerals or characters printed thereon to indicate which player has the next shot and from what position on the board the shot is to be made.

From the foregoing discussion it will be seen that I have provided a highly interesting game

apparatus wherein the skill and accuracy of the players are mainly responsible for the winning of the game, and wherein skill may be acquired from experience and practice.

The term "target" is used hereafter in the appended claims in its broad sense to denote any objective or aiming point whether a receptacle or otherwise at which a projectile is impelled or thrown.

It will, of course, be understood that various changes may be made in the form, details, proportions and arrangements of the parts without departing from the scope of my invention.

What is claimed is:

1. In a game apparatus, a playing board having a target associated therewith, a ball-like projectile having a plurality of pairs of parallel faces upon any one of which it may seat by chance after being thrown, a projector for said projectile adapted to be freely moved about over the board and placed in any desired shooting position thereon with respect to said target, said projector having projectile receiving means and being manually operable to throw said projectile at said target, said playing board having indicia thereon indicating a plurality of predetermined shooting positions with respect to said target, and the faces of said projectile having indicia thereon corresponding to the indicia of said playing board, whereby, after said projectile has been thrown and comes to rest its indicia will automatically denote the next shooting position from which the projectile is to be thrown by said projector.

2. In a game apparatus adapted to be participated in by two or more players, a playing board

having a target associated therewith, a ball-like projectile having a plurality of pairs of parallel faces upon any one of which it may come to rest after being thrown, a propelling device for said projectile adapted to be freely moved about over

the board and placed in any desired propelling position thereon with respect to said target, said propelling device having projectile receiving means and being manually operable to throw

35 said projectile at said target, said playing board having indicia thereon indicating a plurality of predetermined playing positions from which the projectile is adapted to be propelled toward said target, each face of said projectile having

40 indicia thereon denoting one of the players and indicia corresponding to the indicia denoting one of the playing positions of said playing board, whereby, after said projectile has been

45 propelled toward said target and comes to rest on said playing board, its indicia will automatically indicate the next player and also the position from which the projectile is to be propelled toward said target by said propelling device.

3. In a game apparatus, a playing board having a target associated therewith, said playing board having indicia thereon indicating a plurality of predetermined projectile shooting positions with respect to said target, a ball-like

50 projectile having a plurality of pairs of parallel faces upon any one of which it may come to rest after being thrown, a projector for said projectile adapted to be freely moved about over

55 the board and placed in any desired projecting position thereon with respect to said target, said projector comprising a comparatively flat member having an aperture therein for receiving and

60 supporting said projectile, said projector being manually operable to throw said projectile at

65 said target, the faces of said projectile having

70

indicia thereon corresponding to the indicia of said playing board, whereby after said projectile has been thrown and comes to rest its indicia will automatically denote the next position from which the projectile is to be thrown by said projector, the aperture in said projector being of a size to allow any one of the indicia of said play-

ing board to be viewed therethrough, whereby said projector may be located over, and directionally rocked about said indicia as an axis to aim it at said target while constantly maintaining it in proper playing position. 5

RAE J. HEYMER.
